(57) CLAIM

The ornamental design for a wearable ring, as shown and described.

DESCRIPTION

FIG. 1 is a front perspective view of a wearable ring showing my new design;

FIG. 2 is a rear perspective view thereof; and,

FIG. 3 is a right side view thereof, the left side view being a mirror image thereto.

The broken lines shown in the drawings illustrate portions of the ring that form no part of the claimed design.
